(57) **CLAIM**

The ornamental design for a set of load carrier equipment labels, as shown and described.

DESCRIPTION

FIG. 1 is a front view of a first embodiment showing my new design for a set of load carrier equipment labels,

FIG. 2 is a back view thereof;

FIG. 3 is a side view thereof, with the opposite side being a mirror image;

FIG. 4 is a front view of a second embodiment showing my new design for a set of load carrier equipment labels,

FIG. 5 is a back view thereof;

FIG. 6 is a side view thereof, with the opposite side being a mirror image;

FIG. 7 is a front view of a third embodiment showing my new design for a set of load carrier equipment labels,

FIG. 8 is a back view thereof; and,

FIG. 9 is a side view thereof, with the opposite side being a mirror image.
